LAUNDRY IRON SUPPORT

William T. Rickles, Oneonta, Ala.

Application October 24, 1949, Serial No. 123,135

3 Claims. (Cl. 248—117.3)

1

This invention relates to a stand, or support, for hot laundry irons and is of the general type described in my pending application Serial Number 88,617, filed April 20, 1949, now Patent No. 2,584,370.

An object of the invention is to provide a device of the character designated which shall be simple of design, economical of manufacture, light in weight, durable in use and one which shall withstand a high degree of temperature without transmitting sufficient heat to endanger substances with which it might come in contact.

A still further object is to provide a support for hot laundry irons which shall have an insulated body and a rugged metal surface over the body for the iron to rest on, thereby avoiding the necessity of changing the top surface of the support after it has been in use for a short period of time.

A device embodying features of my invention is illustrated in the accompanying drawing forming a part of this application in which:

Fig. 1 is a plan view of the device;

Fig. 2 is a sectional view taken along the line II—II of Fig. 1;

Fig. 3 is a sectional view taken along the line III—III of Fig. 1; and,

Fig. 4 is a side elevational view, partly broken away, showing an iron in place in dotted lines.

Referring now to the drawing for a better understanding of my invention the iron support embodies a flat sheet metal bottom 10, shaped to conform generally to the shape of an iron, upstanding sides 11 and 12, which converge and join at the front, and an upstanding back wall 13 at the rear. The edges of the bottom 10 are turned downwardly at the sides 11 and 12 and back 13 so as to form a downwardly turned flange 14 of approximately $\frac{1}{4}$ of an inch in width all around the bottom 10. The flange 14 fits within and is spot welded along the lower portion of the sides 11 and 12 and back wall 13, as at 15, thereby forming a unitary structure and supporting the bottom approximately $\frac{1}{4}$ of an inch above the bottom edges of the sides and rear walls. The upper edges of the sides 11 and 12 and of the back wall 13 are turned over, inwardly, as shown at 16, and then downwardly, as shown at 17, to form a downwardly opening channel 18 which extends all around the upper edge of the device. A handle 19 is welded to the back wall 13 as at 21.

A plurality of holes 22 are provided in the lower portion of the sides 11 and 12 below the bottom 10. These holes provide means for air to circulate below the bottom 10.

2

A pad of fibrous insulating material 23, such as spun glass, approximately $\frac{1}{2}$ of an inch in thickness covers the bottom 10. Fitting over the pad 23 is a relatively stiff board of insulating material 24, such as asbestos board, having a thickness of approximately $\frac{1}{4}$ of an inch.

Extending around the upper portion of the sides 11 and 12 and the back wall 13 is a pad of insulating material 26 such as asbestos board 10 having a thickness of approximately $\frac{1}{16}$ of an inch. The pad 26 extends upwardly into the downwardly opening channel 18, which channel serves to hold the upper edge of the pad in place and extends downwardly alongside the insulating board 24 to the fibrous insulating material 23, as shown in Figs. 2 and 3, so that its lower edge is held in place by the insulating board 24.

A thin metal plate 27 fits over the insulating material 24, thereby providing a rugged wearing 20 surface upon which the iron, indicated in dotted lines 25, is to rest. The metal plate is narrower than the top so that it does not come in contact with the end and side walls, thereby preventing a transfer of heat to said walls. This provides 25 a hot surface for the iron to rest on thereby saving in electricity need to keep the iron hot. The metal plate 27 is held in place by means of a plurality of downwardly and inwardly turned clips 28 disposed to fit beneath the insulating 30 board 24. A plurality of holes 29 may be bored through the metal plate.

From the foregoing it will be apparent that I have devised an iron support which is rugged, light in weight, simple of manufacture and economical in which the insulation is sufficient to prevent any accident from an overheated iron and sturdy enough to withstand long wear and hard usage. I have found in the actual use of stands constructed in accordance with this invention that a heated iron may be left on the stand indefinitely without damage to substances which might come in contact with the stand. By placing the metal plate over the insulating board 24 the device will withstand extremely hard 45 usage. I have also found that the temperature of the bottom of the stand is greatly reduced by providing the air space below the bottom 10 of the stand, as shown.

While I have shown my invention in but one 50 form, it will be obvious to those skilled in the art that it is not so limited, but is susceptible of various changes and modifications, without departing from the spirit thereof, and I desire, therefore, that only such limitations shall be 55 placed thereupon as are specifically set forth in the appended claims.

What I claim is:

1. In a stand for supporting hot laundry irons, an upstanding rear wall and side walls having inwardly turned over upper edges forming a downwardly opening channel around the upper edge, the side walls of which converge and join at the front, a bottom, a downwardly turned flange along the sides of the bottom welded to the lower inner portion of the back and side walls, there being a plurality of holes along said side walls disposed to permit air to circulate below said bottom, a pad of fibrous insulating material covering the bottom, a relatively stiff board of insulating material above said fibrous insulating material extending around said back wall and said side walls and upwardly into said downwardly opening channel to be retained in place thereby, a second relatively stiff board of insulating material covering the pad of fibrous insulating material and bearing against the lower portion of the first mentioned board to hold it in place.

2. A stand as defined in claim 1 in which the second mentioned board of insulating material is covered with a metal plate held in place by a plurality of downwardly and inwardly turned clips extending through said second mentioned board of insulating material and bent over.

3. In a stand for supporting hot laundry irons, an upstanding rear wall and side walls shaped to conform generally to the shape of an iron, with one end generally rectangular and the other

end with converging sides, the upper edge of the sides and the rectangular end being turned inwardly and downwardly to form a downwardly opening channel, a bottom, a downwardly turned flange extends around the bottom fitting within, and welded to, the back and side walls thereby supporting the bottom above the bottom edges of the back and side walls, said side walls and the flange on said bottom being provided with holes extending therethrough for the circulation of air, a pad of fibrous insulating material covering said bottom, a relatively stiff board of insulating material along each side and across the end, said pad extending upwardly into the downwardly opening channel to be retained in place thereby, a second relatively stiff insulating board covering the fibrous insulating material and bearing against the lower portion of the insulating board extending along the sides and across the end, a metal plate on said second insulating board having a plurality of holes therethrough, and means to retain said metal plate in place.

WILLIAM T. RICKLES.
